US00D995207S

(12) **United States Design Patent** (10) **Patent No.:** **US D995,207 S**
(45) **Date of Patent:** **** Aug. 15, 2023**

(54) **COOKWARE GRIP**

(71) Applicant: **Lagom Kitchen Co.**, Culver City, CA (US)

(72) Inventors: **Amir Tehrani**, Los Angeles, CA (US); **Zachary Rosner**, Los Angeles, CA (US); **Melinda Olsen**, Los Angeles, CA (US); **Hlynur Atlason**, New York, NY (US); **Christopher Santone**, Brooklyn, NY (US)

(73) Assignee: **Lagom Kitchen Co.**, Culver City, CA (US)

(**) Term: **15 Years**

(21) Appl. No.: **29/826,382**

(22) Filed: **Feb. 11, 2022**

(51) LOC (14) Cl. **07-02**

(52) U.S. Cl.

(57) **CLAIM**

The ornamental design for a cookware grip, as shown and described.

DESCRIPTION

FIG. 1 is a perspective view of a cookware grip showing our design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top view thereof;

FIG. 7 is a bottom view thereof; and,

FIG. 8 is a perspective view of the cookware grip shown in an environment of use.

The broken lines in FIG. 8 represent environment and form no part of the claimed design.

1 Claim, 7 Drawing Sheets
